European Design Application No. 005948601 "Cooler" filed Jan. 4, 2019.

(Continued)

Primary Examiner — Terry A Wallace

(74) *Attorney, Agent, or Firm* — Middleton Reutlinger

CLAIM

The ornamental design for a cooler, as shown and described.

DESCRIPTION

FIG. 1 is a front perspective view of a cooler design; FIG. 2 is a rear perspective view of the cooler design of FIG. 1;

FIG. 3 is a front view of the cooler design of FIG. 1; FIG. 4 is a rear view of the cooler design of FIG. 1; FIG. 5 is a first side view of the cooler design of FIG. 1; FIG. 6 is a second side view of the cooler design of FIG. 1; FIG. 7 is a top view of the cooler design of FIG. 1; FIG. 8 is a front perspective view of the cooler design with the lid in an open position;

FIG. 9 is a rear perspective view of the cooler design of FIG. 8;

FIG. 10 is a front view of the cooler design of FIG. 8; FIG. 11 is a rear view of the cooler design of FIG. 8; FIG. 12 is a first side view of the cooler design of FIG. 8; FIG. 13 is a second side view of the cooler design of FIG. 8; and,

FIG. 14 is a top view of the cooler design of FIG. 8.

The broken line disclosure represents unclaimed boundary and/or portions of the cooler in which the design is embodied.

1 Claim, 14 Drawing Sheets

Examination report mailed in DE Patent Application No. 102019200063.0 dated Oct. 15, 2019.

Notification to Grant Patent Right for CN Design Application No. 201930331393.8 dated Oct. 29, 2019.

CN Patent Application No. 201911066985.7 entitled "Cover for a Cooler" filed Nov. 4, 2019.

DE Patent Application No. 102019200063.0 entitled "Mobile Cooling Box with User Interface Module" filed Jan. 4, 2019.

DE Patent Application No. 102019200064.9 entitled "Mobile Cooling Box with Latch Handle Opening" filed Jan. 4, 2019.

DE Patent Application No. 102019200070.3 entitled "Mobile Cooling Box With Hinge Module" filed Jan. 4, 2019.

U.S. Appl. No. 29/711,905 entitled "Cover for a Cooler" filed Nov. 4, 2019.

U.S. Appl. No. 29/711,906 entitled "Cover for a Cooler" filed Nov. 4, 2019.

U.S. Appl. No. 16/728,715 entitled "Mobile Cooling Box with Ice Maker" filed Dec. 27, 2019.

U.S. Appl. No. 16/728,623 entitled "Mobile Cooling Box with User Interface Module" Dec. 27, 2019.

U.S. Appl. No. 16/728,687 entitled "Mobile Cooling Box with Latch Handle Opening" filed Dec. 27, 2019.

U.S. Appl. No. 16/728,657 entitled "Mobile Cooling Box with Hinge Module" filed Dec. 27, 2019.

Examination report mailed in EU Design Application No. 005948601-0001/005948601-0030 dated Jan. 9, 2019.

CN Design application No. 201930331393.8 entitled "Cooler" filed Jun. 25, 2019.

DE Design Application No. 102019200067.3 entitled "Mobile Cooling Box With Ice Maker" filed Jan. 4, 2019.

U.S. Appl. No. 29/697,070 entitled "Cooler" filed Jul. 3, 2019.

U.S. Appl. No. 29/697,069 entitled "Cooler" filed Jul. 3, 2019.

Decision to Grant mailed in DE Patent Application No. 1020192000681 dated Oct. 15, 2020.

Examination report mailed in DE Application No. 102019200065.7 dated Sep. 30, 2019.
